UNITED STATES PATENT OFFICE.

DAVID C. MEEHAN, OF COLUMBUS, OHIO.

PIGEON-HOLE CASE.

SPECIFICATION forming part of Letters Patent No. 357,403, dated February 8, 1887.

Application filed October 19, 1886. Serial No. 216,620. (No model.)

To all whom it may concern:

Be it known that I, DAVID C. MEEHAN, a citizen of the United States, residing at Columbus, in the State of Ohio, have invented a new and useful Improvement in Pigeon-Hole Cases, of which the following is a clear, full, and exact description, reference being had to the accompanying drawings, making a part of this specification, in which—

1c Figure 1 is a front view of a case of pigeon-holes with my improvements attached. Fig. 2 is a vertical section of the same with the shutters closed and locked. Fig. 3 is a vertical section showing the shutters unlocked and one shutter raised. Fig. 4 shows detached views of sliding knob for supporting the raised shutter. Fig. 5 is a detached view of the locking device. Fig. 6 is a detail showing a modification of the knob and pin.

20 My present invention relates to means for locking the shutters of a case of pigeon-holes when closed and for holding up the shutters when raised; and it consists in the devices hereinafter described and claimed.

25 To enable others skilled in the art to make and use my invention, I will proceed to describe the exact manner in which I have carried it out.

It has been usual in pigeon-hole safes or 30 cases to attach a button or lug on the ceiling of each compartment to be turned out to catch and hold the shutter of that compartment when raised. To operate this button necessitated the use of both hands—one to raise the 35 shutter and the other to turn the button. This button, when turned in position to catch and hold up the shutter, was directly in the way in drawing a package of papers from the pigeon-hole and in placing a package in the 40 case. To overcome these objections is one purpose of my present invention.

In the drawings, A represents a case of 45 pigeon-holes, B the horizontal divisions, and C the shutters, which slide up and down in the usual and well-known manner. Through the lower edge of each shutter I pass a sliding pin, D, provided with a suitable head, d, and with an enlargement, d', on the inner end to prevent the possibility of the pin being entirely withdrawn from the shutter. This pin 50 slides snugly through a perforation in the lower part of the shutter, as shown in Figs. 2

and 3. When the shutters are closed, the pin D lies in the position shown in Fig. 2; but when it is desired to raise a shutter it is only 55 necessary to catch the head d with the hand, withdraw the pin D as far as the enlargement d' will permit the withdrawal, raise the shutter clear of the pigeon-hole, and again push in the pin, as shown in Fig. 3, whereby the 60 shutter is securely held in its raised position. The whole operation is done with one hand, leaving the other hand to handle the package free from any obstruction in the pigeon-hole.

65 It is evident a quick screw could be used instead of the sliding pin without departing from the spirit of my invention.

When the shutters are all closed down and it is desired to lock them in position, it is only 70 necessary to move the lever E, by which the transverse bar F is partially rotated, and the pawls G are brought against the upper line of shutters, safely securing them in that position until the action of the lever E is reversed and 75 the pawls removed from the shutters. The lever E may be locked or otherwise secured in position.

The grooves a, in which the shutters move, are extended upward into the hollow cornice 80 of the case, as shown in Fig. 3, the space between the back and front of said cornice being just large enough to receive and permit the passage of said shutter. By this construction the upper shutter, when raised, is inclosed. 85

Having described my invention, what I claim as new, and desire to secure by Letters Patent, is—

1. In a pigeon-hole case, a sliding pin in combination with the shutter, substantially as 90 and for the purpose herein set forth.

2. An improved pigeon-hole case, having grooved sides and a hollow cornice, in combination with the sliding shutters, the upper one of which when raised being concealed within 95 said cornice, the sliding pins for operating the shutters, and a transverse bar and pawls for holding the shutters in a closed and locked position, substantially as herein described.

DAVID C. MEEHAN.
